UNITED STATES PATENT OFFICE.

FRANK J. VIERLING, OF MINNEAPOLIS, MINNESOTA, ASSIGNOR TO CLOVER G. IRVINE,
OF MINNEAPOLIS, MINNESOTA.

PENCIL.

Application filed June 3, 1926. Serial No. 113,450.

This invention relates to pencils of the automatic type, and specifically to a pencil of that class wherein the writing point of the contained lead may be advanced or retracted by a screw-threaded action between two telescoping members, the inner member carrying the lead. In addition thereto the invention includes means permitting a step-by-step advance of the lead towards writing position, under the influence of pressure tending to cause telescopic movement of said members, the one within the other.

It is the primary object of the invention to produce a pencil such as described, which may be economically manufactured, which will operate with a maximum of efficiency, and in which the number of the parts are reduced to the minimum.

Other objects of the invention will be made apparent in the following specifications when read in connection with the accompanying drawings forming a part thereof.

In the accompanying drawings, which illustrate the invention, like characters indicate like parts throughout the several views.

Referring to the drawings:

Fig. 1 is an elevation of the improved pencil;

Fig. 2 is a view principally in longitudinal central section;

Fig. 3 is a transverse section taken on the line 3—3 of Fig. 2, on an enlarged scale; and

Fig. 4 is a fragmentary detail view principally in section taken on the line 4—4 of Fig. 3.

The improved pencil comprises a casing made up of telescopically connected inner and outer members 5 and 6, the latter being of resilient material, and a lead holder 7. The outer end of the casing member 6 is contracted to a point 8 through which the leads α , held by the holder 7, are projected. The outer end of the casing member 5 is circumferentially expanded to afford a seat 9 for a cap-like holder 10 in which is mounted an eraser 11. This holder 10 provides a displaceable closure for the rear end of the casing member 5.

A disk-like partition 12 is rigidly secured in the casing member 5 and is spaced from the holder 10. The casing member 5 between the holder 10 and partition 12, forms a spare lead compartment 13. The holder 7 is in the form of a longitudinally split sleeve axially located in the casing member 6 and rigidly secured to the partition 12 by a rod 14.

Said lead holder 7 has its inner end portion telescoped onto the rod 14 and rigidly secured thereto, and which rod affords a stop or an abutment for the lead α in the holder 7.

The casing members 5 and 6 are connected for relative axial movement by co-operating cam-acting ratchet lock elements which include a circumferential bead 15 on the interior of the casing member 6 and circumferential axially spaced corrugations 16 on the exterior of the casing member 5. These lock elements 15 and 16 are formed by being pressed directly from the respective casing members 5 and 6.

The casing member 5 is longitudinally split at 17 transversely through the lock elements 16 to permit circumferential contraction thereof. Said lock element 15 is adapted to enter any one of the lock elements 16 to hold the casing members 5 and 6 in different axial adjustments in respect to each other. By applying slight axial pressure to both casing members 5 and 6 in opposite directions, said casing members may be relatively axially adjusted by a step by step movement produced by the lock element 15 successively entering the lock elements 16. When pressure is applied to both casing members 5 and 6 in opposite directions, the lock element 15 and engaged corrugation 16 will be cammed out of interlocking engagement, the walls defining the slot 17 yielding under such pressure, and the lock element 15 will enter the adjacent corrugation 16. While the lock elements 15 and 16 are interlocked the casing members 5 and 6 are free for relative turning movement.

When the lead α becomes worn it may be further projected by applying pressure to both casing members to move the lock element 15 into the next lock element 16. The spacing of the lock elements 16 is such that the lead α is always projected a predetermined distance outward from the point 8. Access may be had to spare leads in the compartment 13 by removing the holder 10 containing the eraser 11.

The compartment 13 may be filled with spare leads α by removing the holder 10 to afford access to said compartment. These spare leads α are removed one at a time as they are needed through a relatively small passageway 18 in the side of the casing member 5 just above the partition 12. This passageway 18 is normally closed by the casing member 6 and to uncover said passage-

way it is only necessary to axially draw said members apart a relatively short distance.

To deflect the spare leads α through the passageway 18 the casing member 5 is provided with an oblique false bottom 19. By axially separating the casing members 5 and 6 the holder 7 is withdrawn from the casing member 6 so that a new lead may be inserted therein. The interlocking engagement between the members 15 and 16 is such that the casing members 5 and 6 will be positively held against relative axial separation under a pressure applied to the leads α during the writing action.

15. What I claim is:

1. A pencil comprising a barrel carrying a bead and a tubular shell telescopically slideable therein, said shell being composed of resilient material and provided with a helical

thread on its inner portion adjacent said open end, adapted for interengagement with said bead, and a smooth portion extending beyond the end of said barrel, the inner portion of said shell being longitudinally slotted transversely of said thread and through said open end, and a lead carrier mounted on said shell substantially as and for the purpose set forth.

2. A pencil comprising a barrel and a shell telescopically mounted therein, a spare lead compartment in said shell, said compartment having a bottom wall sloping to one side, a lead passageway extending through the side of said shell at a point adjacent the lower edge of said wall, and a removable closure for the upper end of said compartment.

In testimony whereof I affix my signature.

FRANK J. VIERLING.
